ABSTRACT OF THE DISCLOSURE

This invention relates to a carton sealing machine and a method of sealing cartons by enveloping the cartons with a flexible diaphragm under positive pressure. More particularly, this invention comprises a carton sealing machine having means for automatically moving cartons into a sealing area, enveloping cartons with a pressurized flexible diaphragm while sealing the cartons and thereafter removing the cartons from the sealing area.

An object of the present invention is to provide an efficient machine and process for tightly sealing a carton filled with paper sheets. Another object is to apply even pressure to stacks of paper sheets in a carton so that excess air and moisture are removed from the carton during sealing. Still another object of the present invention is to provide a mechanism that will automatically accomplish the sealing of cartons with a minimum of attendance and supervision.

These and other objects are accomplished in accordance with the following description and drawings in which:

FIGURE 1 is a side elevation of the machine partly broken away to illustrate one arrangement of parts which can be used in the present invention;

FIGURE 2 is a side elevation of the machine of FIGURE 1 with the diaphragm in exhaust position;

FIGURE 3 is a side elevation of the machine of FIGURE 1 with the diaphragm in pressure position; and

FIGURE 4 is a diagram showing one circuit arrangement which can be used to practice the invention described herein.

The carton sealer machine 1 is a hollow cabinet with a chamber 3 which is divided by a flexible diaphragm 6 into a lower portion 4 and an upper portion 5. The diaphragm is secured to the inside of the chamber at 15 to form an airtight seal. Within the lower portion a platen 8, mounted on a hydraulic cylinder 9, is moved vertically responsive to pressure within the cylinder. The hydraulic circuit includes pressure switch 58 located at the bottom of the cabinet.

A blower 12 and valve 14 are connected to air manifold 16 to force air under pressure to upper portion 5 and to exhaust air from portion 5. In FIGURE 2 the platen 8 with carton 25 is shown raised and the diaphragm 6 is in exhaust position. In FIGURE 3 the diaphragm 6 is shown in pressure position tightly enveloping carton 25.

Referring to FIGURE 4, current is circulated through 46 when push button switch 52 is actuated to pass through pressure switch 58 and starter 60 to run pump motor 56 through the starter so that hydraulic fluid is fed in the hydraulic system and under hydraulic pressure platen 8 is raised in the chamber.

Once carton 25 reaches the upper limit within the chamber, pressure switch 58 is tripped to inactivate the hydraulic motor and no increase in hydraulic pressure takes place. At the same time, current is routed through relay 62 to activate the blower solenoid 64 in the blower unit. Solenoid 64 is connected to valve 14. It will be

2

understood that blower motor 12 runs constantly and normally exhausts air from the upper portion of the chamber, drawing the diaphragm to the top of the chamber as seen in FIGURE 2. Upon activation of solenoid 64, the flow of air is reversed and pressurized air is forced into the upper portion 5 to urge the diaphragm in contact with the carton being sealed.

Time relay 68 is started simultaneously with the activation of relay 62 and after about 15–25 seconds, relay 68 interrupts the current. Fuse 65 is provided to cut the circuit through contact relay 63 when overload occurs. Simultaneously, current flows to down solenoid 72 through limit switch 69 and moves this solenoid to lower platen 8. Fuses 77 and 79 are included as a safety measure. Down solenoid 72 is connected to a valve in the hydraulic system. Upon activation, solenoid 72 opens the hydraulic valve and the platen is lowered while at the same time the blower air flow is reversed to again apply vacuum to the upper portion 5 of the chamber, completing one cycle of operation.

It will be noted that push button switch 76 is normally open and that the blower circuit normally is closed. At start up of the carton sealing machine, current passes through closed switch 80 to blower starter 84 to run blower motor 12. Thus the blower motor 86 is normally running to raise the diaphragm to vacuum position. Starting the pump begins a complete cycle which automatically raises the platen until the motion is cut off, at which time the blower air flow is reversed and time relay 68 is set. After a predetermined length of time, the platen is lowered by gravity when a valve is opened in the hydraulic system whereupon the blower returns to normal operation.

A pair of overloads 57 and 87 are provided in both the pump circuit and the blower circuit, respectively, for safety purposes. Fuses 50 and 51 are also included in the circuit. Control panel 20 houses push button switches 52, 54, 76, 80 and 82 but it will be understood that once the machine is connected to a source of electric power, only switch 54 need be actuated. Switches 52, 76, 80 and 82 are provided to start or stop pump motor 56, solenoid 72 and blower motor 86 independently of the automatic operation of the carton sealing machine.

While I have described the preferred embodiment of my invention, it is to be understood that it is capable of other adaptations and modifications within the scope of the appended claims.

Having thus described my invention, what I claim as new and desire to secure by Letters Patent of the United States is:

1. A carton sealing machine comprising an enclosed chamber and a flexible diaphragm substantially horizontally disposed within said chamber, said diaphragm dividing said chamber into a lower portion and an airtight upper portion, said lower portion having an ambient atmospheric environment, a platen mounted on a hydraulic cylinder in said lower portion, said platen being vertically movable within the lower portion of said chamber for moving a carton towards and away from said diaphragm, air passage means leading into said upper portion above said diaphragm and blower means connected to said passage means for compressing and exhausting air within said upper portion whereby said diaphragm can be urged by air pressure to envelop a carton on said platen and thereafter withdrawn from said platen as the air is exhausted from said upper portion.

2. The machine of claim 1 wherein said platen is hydraulically raised by a pump within a hydraulic system and a pressure switch is associated with said pump to disconnect same when said platen reaches raised position.

3. The machine of claim 2 wherein said pressure switch is connected to a time relay and said time relay is associ-

ated with a valve in said hydraulic circuit whereby upon actuation of said pressure switch said time relay is activated to open said valve after a predetermined time permitting said platen to move downwardly.

4. The machine of claim 1 wherein a control switch is operatively associated with said blower means and the flow of air within said air passage means is reversed upon the actuation of said switch to move the diaphragm to pressure position.

5. The machine of claim 3 wherein a control switch is operatively associated with said blower means and said switch is connected to said time relay whereby after the predetermined time said switch is activated, and the direction of air within said passage means is reversed to move the diaphragm to vacuum position.

6. A process for sealing a carton comprising exhausting air from a sealed chamber to flex a diaphragm upwardly and positioning an assembled and glued carton

on a vertically movable supporting surface, raising said surface and carton to a predetermined position below the diaphragm, forcing air into said sealed chamber to establish pressure above said diaphragm and enveloping at least part of said carton with said diaphragm in pressure position for a predetermined time to seal same, exhausting air from said chamber to withdraw the diaphragm from the sealed carton and lowering said surface and carton to the original starting position.
